UNITED STATES PATENT OFFICE.

DAVID KNOPFLER, OF NEW YORK, N. Y.

CAP.

Application filed November 21, 1923. Serial No. 676,172.

To all whom it may concern:

Be it known that I, DAVID KNOPFLER, a citizen of the United States, and resident of the city of New York, borough of Manhattan, in the county and State of New York, have invented a new Improved Useful Cap, of which the following is a specification.

My invention relates to improvements in caps and the objects in my improvements are—

First—to provide a cap that can be adjusted to suit different conditions of the weather.

Second—to provide a cap that can be easily manufactured and consequently at a comparatively low cost.

Third—to provide a cap that is reversible from the front to the back and vice versa.

I obtain these objects by the construction illustrated in the accompanying drawings.

Figure (1) is a front or back view of the cap with the flaps folded upwardly.

Figure (2) is a view similar to Figure (1), but with the chin flaps folded in a different position.

Figure (3) is a side view of the cap showing how the side flaps protect the ears of the wearer.

Figure (4) is a front view of the cap showing the side flaps secured under the chin of the wearer.

Figure (5) is a side view of Figure (4).

Similar numerals refer to similar parts throughout the figures.

My cap is especially suited for women and children, for the protection of the head especially in cold weather. It is usually knitted, although I do not limit myself to any method of construction. The parts, for example, could be cut out of woven material.

The cap consists essentially of five (5) parts, the head portion (7), the front and back flaps (9) and (10) and the side flaps (11) and (12). The two side flaps, and the front and back flaps are all secured to the rim of the head portion (7). The head portion (7) I prefer to make of spherical contour similar to the upper part of the head. To the center of the top of the head portion (7) I may attach a tassel (8) or other ornamentation, but this does not constitute any part of my invention. The front and back flaps (9) and (10) are each se-

cured along their lower edge to the lower edge of the head portion (7) and each of these flaps runs substantially half way around the edge of the head piece (7). The front and back flaps (9) and (10) gradually decrease in height as shown. The front and back flaps can be raised or lowered at will, to protect the forehead or the back of the neck of the wearer, and are so formed that when they are in their upper position, the curvature of the material is such as to hold them in place. This curvature also enables the back flap to fit snug against the back of the head, as shown in Figure (5). I also provide the cap with two side flaps (11) and (12), one on each side of the cap and secured to the rim of the head portion (7). The side flaps (11) and (12) are secured to the lower edge of the head portion (7) under the front and back piece (9) and (10). The side flaps (11) and (12) are both similar in shape, and symmetrical on both sides of a central line passing through the center of the cap, as shown in Figure (5), they are also secured to the head piece (7) symmetrically with reference to the front and back flaps (9) and (10). The side flaps (11) and (12) are of such a length that when in use their ends overlap under the chin of the wearer. The end of one flap is buttoned to, or other-wise secured to the end of the other flap, as shown in Figures (4) and (5). I therein show the ends of the side flaps provided with a button hole (16) and a button (15), for securing the ends together. The button hole (16) in the side flap (11), engages with the button (15) on the side flap (12) and vice versa. The side flaps (11) and (12) are adapted for use, either to solely protect the wearer's ears, as shown in Figure (3), or to protect both the ears and the throat, as shown in Figure (4). When the side flaps are not adjusted under the chin their ends can be secured at the back of the head, as shown in Figure (3), at which time the ears will be thoroughly protected. In this position the ends (13) and (14) of the side flaps are folded rearwardly and maintained in substantially horizontal position for a portion of their length about the neck of the wearer. If however, it is not desired to protect the ears, then the side flaps, as well as the front and back flaps (9) and (10) can be placed in their upper position, as shown in Figures (1) and (2) and both

ends of the side flaps can be brought to the front or to the rear, as shown in Figure (2) or one end (13) for example, can be brought to the front and the other end 5 (14) to the rear, as shown in Figure (1). Buttons 18 are arranged on the head portion 7 substantially at the front and rear thereof which are engaged by buttonholes 16 in the ends of the side flaps, thereby 10 to maintain the latter in their selected upper position. When the side flaps (11) and (12) are in their upper position they are folded over on themselves substantially at right angles to their lengths, thereby to 15 bring their ends (14) and (13) respectively, into a horizontal position, as shown.

It is seen, by this construction, that I have provided a cap which can be adjusted in many ways. There are four adjustable 20 flaps, and each flap can be adjusted virtually independent of the other. This is highly desirable in a cap for general use, in all kinds of weather. I prefer to make my cap of a material which will provide a means 25 of ventilation. In the drawing I have illustrated a material in which I have knitted parallel rows of ventilating zones (24). These zones are knitted in such a way as to permit free movement of air there- 30 through and they may be placed at any distance apart best suited to accomplish the purpose intended.

I appreciate that many modifications can be made in the form of the parts going to 35 make up my complete cap and I do not limit myself to the construction and form disclosed, but what I claim as my invention and wish to cover by Letters Patent is—

1. A cap comprising a headpiece, side flaps depending therefrom, said flaps adapted to be moved into upper and lower position, the ends of the side flaps when in upper position adapted to be folded over to assume a substantially horizontal position for a portion of their length on said headpiece and means on said headpiece positioned substantially midway between the apex and base thereof to maintain the ends of said side flaps in folded-over position. 40

2. A cap comprising a headpiece, front and rear flaps depending from said headpiece and adapted to be moved into upper and lower position, a flap on each side of the headpiece depending therefrom said side flaps partially overlapping the front and rear flaps, the side flaps adapted to assume a horizontal folded-over position for a portion of their length on said headpiece when in raised position, means on said headpiece positioned substantially midway between the apex and base thereof adapted to maintain the said flaps in raised position, and means for detachably securing the said flaps under the chin or the back of the neck of the wearer when said side flaps are in lowered position, the ends of the said flaps in lowered position adapted to be folded rearwardly to assume a horizontal position for a portion of their length. 50

In testimony whereof I have signed my name to this specification in the presence of two subscribing witnesses.

DAVID KNOFFLER.

In the presence of—
ARTHUR HOWURTY,
AL SHELLY.
